HAT

Elizabeth Carrozza, Woodside, N. Y.

Application June 21, 1955, Serial No. 36,610

Term of patent 14 years

(Cl. D3—13)

Fig I

Fig II

Fig III

The essential features of my design reside in the portions shown in solid lines on the drawing.

This application is a continuation in part of my application Serial No. D. 32,422 filed September 24, 1954, and now abandoned.

I claim:

The ornamental design for a hat, substantially as shown and described.
